UNITED STATES PATENT OFFICE.

OSCAR W. NORBERG, OF ALAMOSA, COLORADO.

PNEUMATIC TOOL.

1,107,179.

Specification of Letters Patent. Patented Aug. 11, 1914.

Application filed March 6, 1914. Serial No. 822,794.

To all whom it may concern:

Be it known that I, OSCAR W. NORBERG, a citizen of the United States, residing at Alamosa, county of Alamosa, and State of Colorado, have invented certain new and useful Improvements in Pneumatic Tools, of which the following is a specification.

This invention relates to tools, and more particularly to power driven breast tools, and has for its primary object to provide, in a device of the class described, a motor actuated by fluid pressure which shall be of maximum efficiency.

A further object of the invention is to provide a device of the character described, adapted to be operated by fluid pressure, such as compressed air, which utilizes to advantage the entire fluid pressure, and the speed of which is readily controllable by the tool operator.

A still further object of my invention is to provide a tool, preferably for drilling, which is simple in construction, composed of comparatively few easily assembled parts, so arranged as to be less liable to breakage or derangement, and yet which will prove thoroughly efficient in operation.

With these objects in view, together with others which will appear as the description proceeds, my invention consists in a tool of the character described, comprising a casing, within which is arranged a rotor or rotary piston adapted to rotate a spindle to which the tool point or drill is attached; a head secured within the casing adjacent the rotary piston, vanes arranged upon the said piston in circular series, ports in the said head communicating with, and adapted to project a current of air against, said vanes; a valve for controlling the flow of air through said ports, and means for admitting air to the casing.

My invention further consists in the arrangement thus briefly described, further characterized by means for controlling the said valve directly from the handle or hand grip usually held by the operator in directing the point and supporting the instrument.

My invention further consists of the arrangement of pockets adjacent the vanes upon the rotary piston within which the air under compression is adapted to be projected, the outlets of the said pockets through which the air escapes being so arranged as to permit of the fluid further aiding in the rotation of the piston by its ex-

pansion upon escape from the restricted pocket.

My invention further consists in the arrangement of the said vanes being angularly disposed with relation to the direction of rotation of the piston, the ports within the fixed head being located to directly cover the series of vanes, and to direct a current of air angularly in the direction of rotation of the said piston into the pockets between the said vanes.

My invention still further consists in the provision of a casing comprising a cylinder with a reduced neck, the said reduced neck being provided with a rotatable hand grip, the rotary piston and fixed head located within the cylinder, a valve for controlling the flow of air through the ports in said head, and the stem for controlling the valve being reduced to fit within the reduced neck, and means connecting the hand grip with the valve stem whereby upon rotation of the said grip the valve will be actuated.

My invention still further consists in the novel combination and arrangement of parts, all as will be more fully described hereinafter, and more specifically pointed out in the appended claims.

My invention will be more readily understood with reference to the accompanying drawings forming a part of this specification and in which—

Figure 1 is a plan view of a breast tool constructed in accordance with my invention, Fig. 2 is an enlarged longitudinal section taken substantially upon the line 2—2 of Fig. 1, Fig. 3 is a section taken upon the line 3—3 of Fig. 2, the drill chuck and breast plate being removed, Fig. 4 is a fragmentary horizontal section taken upon the line 4—4 of Fig. 2, and looking in the direction indicated by the arrows, Fig. 5 is a sectional view taken upon the line 5—5 of Fig. 4, Fig. 6 is an edge view, partly in section, of the improved piston employed in carrying out my invention, Fig. 7 is a face view thereof, Figs. 8 and 9 represent respectively an edge view partly in section, and a face view of the improved head, Fig. 10 is an edge view of the valve employed for controlling the flow of air to the piston, Fig. 11 is a front elevation thereof, Fig. 12 is a rear elevation of said valve, Figs. 13 and 14 represent respectively a front elevation, and side view partly in section, of my improved valve operating stem, and Fig. 15 is an enlarged

section taken substantially upon the line 15—15 of Fig. 1.

Referring now more particularly to the drawings, 1 represents generally the casing within which the improved piston and piston operating mechanism is located, and which it has been found most convenient to construct in the shape of a cylinder. Extending from one side of the cylinder is a 10 reduced neck 2, interiorly threaded at its outer extremity for the reception of a nipple 3 leading from a suitable source of fluid supply. The construction of the reduced neck may be arranged and connected to the cylinder 1 in any preferred manner, it has been found however that the arrangement shown in the present instance proves most practical and efficient for the purposes, and is constructed separately from the cylinder, being 15 shouldered as at 4 to be engaged by a nut 5 threaded to the outer end of the cylinder 1. The reduced neck 2 is provided with a rotatable hand grip 6, held upon the said reduced neck at one end by the enlarged 20 portion of the neck, and at the other end in any suitable manner, such for instance, as a shoulder or flange 7 upon the nipple 3. Openings 8 may be provided in the hand grip in order that lubricant may be introduced to reduce friction upon rotation of the grip. To the side opposite to that with which the reduced neck is connected to the cylinder 1, is located a housing 9 within which is adapted to operate mechanism for 25 furthering rotation of the spindle to which the tool is attached, and, to the end that the interior of the housing and parts contained therein may be readily accessible, the same is composed of several separable sections. The body portion 10 of the housing is preferably secured to the cylinder 1 and extends longitudinally therebeyond, providing a barrel 11, communicating with the central portion longitudinally of the cylinder, and a housing 12 thereabove for the 30 reception of mechanism to be more specifically described later. The housing 12 in this instance is substantially narrow in width and is circular in shape, being provided adjacent its inner circular edges with screw threads 13 for the reception of the sections 14 and 15 constituting housing sections. In the present instance it is to be observed that the drill or tool is disposed at 35 right angles to the mechanism for operating the same and to this end a spindle 16, suitably journaled in the boxes 17 to reduce friction, and provided at one end with thrust bearing 18, is extended through the 40 housing constituting the member 12, and members 14 and 15, at right angles to the direction assumed by the cylinder 1 and the reduced neck 2 and barrel 11. The spindle extends beyond the housing section 15 and 45 is threaded as at 19 to receive a chuck or

other tool retaining member 20, adapted to retain the drill or tool 21. The housing section 14 at the opposite side of the housing member 12 is extended as at 22 and threaded interiorly as at 23 to receive the shank 24 of a breast plate 25 for applying pressure longitudinally of the drill or bit during the cutting operation. A worm 26 is suitably journaled as at 27 within the barrel 11, and has its shaft 28 extended into the cylinder 75 or casing 1. A worm gear 29 is mounted upon the shaft or spindle 16 and is of sufficient diameter to intermesh with the worm 26, the same being located within the housing and housing sections 14 and 15 and, as 80 has been above more fully described, is readily accessible by reason of the threaded connection of the said housing sections with the body portion 12 of the housing. The end of the shaft 28 remote from the cylinder end of the barrel 11 is provided with a thrust bearing 30, which is readily accessible by reason of the nut 31 and cap 32 adapted to fit over the end of the barrel. By this construction it is obvious that upon rotation of the shaft 28 carrying the worm 26, rotary motion will be imparted, through the worm gear 29, to the angularly disposed shaft 16 carrying at its end the drill or tool 21. It is also obvious from the disclosure 85 that owing to the numerous antifriction devices in which the several movable parts are journaled, together with the ready accessibility of these parts for the application of lubricants, a minimum amount of power 90 only will be required to impart motion to the spindle. It is also to be observed that as the breast plate is in direct alinement with the point of the cutting tool, the required amount of force or pressure may be 95 correctly directed to the tool point to the best advantage.

The improved means for giving initial movement to the mechanism above described, will now be taken up more fully in 100 detail, and comprises a rotor, or rotary piston 33, which is mounted securely upon the end of the shaft 28 of the worm extending into the cylinder or casing 1. This rotary piston is in substantially the shape of a 105 disk, being enlarged at its center as at 34 to provide the maximum surface for engagement with the shaft 28. The piston is provided adjacent its periphery with a circular series of radial vanes 35, each of which extends entirely through the piston and is V-shaped in transverse section forming a pocket 36; the inlet and outlet 38 and 39 of which communicates with the opposite faces of the piston from said pocket in a direction 110 rearwardly with relation to the direction of rotation of the piston. As will be seen from this arrangement, it is desired to have the air admitted to the pockets at an angle, 115 and in the direction of rotation of the pis- 120

ton, and also it is desired to exhaust the air in the same manner. It has been found in practice that by this method the maximum amount of power may be utilized from the 5 source of fluid energy, the air under pressure impinging against the walls of the pockets 36 behind the vanes, in the direction of rotation, and the escape rearwardly therefrom permits of the energy, caused by 10 the expansion of the air in passing from the restricted opening 38, of the back pressure incident thereto being utilized to aid in the rotary motion of the piston. Adjacent the outer face of the rotary piston is fixedly secured a head 40 which acts as a barrier to withhold the fluid pressure from the piston, and this head is dished at its medial portion and provided with a thrust bearing 41 for the support of the end of the worm shaft 20 supporting the rotary piston. An oil channel 42 is provided in said head, communicating at its inner end with the said thrust bearing, and communicating with a port or inlet in the cylinder 1 at its other 25 end in order that the thrust bearing 41 may be properly lubricated. For the purpose of admitting air to the piston above described, the head 40 is provided with a plurality of ports or ducts 43, there being but two ports 30 illustrated in the present instance and these being positioned upon the head at diametrically opposite points, and in such position as to communicate, or direct a current of air or other fluid directly into the pockets 36 35 between the several vanes of the piston. To the end that the fluid may be directed to the pocket 36 at an angle to attain the most efficiency from the fluid, the ports 43 extend from one face of the head to the face adjacent the rotary piston at an angle sufficient 40 to cause the air to be directed into the said pockets and impinge against the walls thereof. A valve 44 is provided upon the outer face of the head to control the flow of 45 air through said ports, and this valve comprises in the present instance a ring, provided with a flange 45 adapted to fit behind, and rotate within a portion of the enlarged end of the reduced neck 2. This 50 valve is provided at intermediate points in its inner surface, or surface adapted to be adjacent the head 40 when assembled, with a plurality of spaced portions or feet 46 whereby the friction incident to high pressure 55 of the fluid within the cylinder is reduced, and the valve is thereby rendered more easily operable. The ring 44 is provided with a pair of openings 47 at points diametrically opposite, which are adapted 60 to extend through the entire thickness of the ring and, when it is desired to operate the mechanism, to register with, or to admit air to, the angularly disposed ports 43 in the fixed head 40. The outer face of the ring 65 44 is provided at opposite points with

grooves 48, within which the ends 49 of a valve stem 50 are adapted to engage. The valve stem 50 is preferably hollow to permit of the passage of air from the air source to the head 40, and is reduced to permit of its insertion snugly within the reduced neck 2 of the device. The reduced neck 2 is provided with a slot 51 extending a short distance around its circumference to permit of the rotary play of a screw or other securing element 52, which is utilized as a connecting means between the rotatable hand grip 6, and the stem 50 of the valve.

It is obvious that upon application of fluid under pressure to the interior of the 80 cylinder, and upon manipulation of the valve 44 to permit the flow through the ports 43 of the head, and into the pockets 36 between the vanes in the piston, motion will be imparted through the worm 26 and worm 85 wheel 29 to the shaft 16, to operate the bit or tool point 21, in the desired manner. The air is permitted to escape from the cylinder, after having been utilized to rotate the piston, through the port 53 in the end of the 90 cylinder 1.

I claim:

1. In a device of the class described, a casing, a piston within said casing, said piston provided with a circular series of vanes, a head in said casing adjacent said piston and provided with angularly disposed ports adapted to direct a current of fluid against said vanes, a valve co-operating with said head to regulate the flow of the fluid to said piston, a rotary hand grip on said casing, and means connecting said hand grip with said valve, and a spindle in connection with said piston, substantially as described.
2. In a device of the class described, a casing provided with a reduced neck, a rotatable hand grip on said neck, a rotary piston in said casing, said piston provided adjacent its periphery with a circular series of angularly disposed vanes, a tool spindle in connection with said piston, a head adjacent said piston provided with oppositely disposed angularly inclined ports, communicating with said vanes, a valve for opening and closing said ports, said valve controlled by a stem fitting within said reduced neck and in connection with said rotatable hand grip, and means for admitting air to said reduced neck, substantially as described.
3. In a device of the class described, a 120 casing comprising a cylinder with a reduced neck, a hand grip mounted for rotation upon said reduced neck, a rotary piston within said cylinder provided with a circular series of angularly disposed vanes, a worm in connection with said piston and a gear in mesh with said worm for rotating the spindle, a head adjacent said piston provided with a plurality of angularly disposed ports for directing the current of fluid against said 125

vanes, a valve for opening and closing said ports, a valve stem with a reduced portion to fit within said neck, and a connection between said valve stem and said hand grip, substantially as described.

4. In a device of the class described, a casing comprising a cylinder having a reduced neck, a hand grip mounted for rotation upon said neck, a rotary piston within 10 said cylinder provided with a circular series of pockets, a spindle adapted to be rotated by said piston, a head adjacent said piston provided with a plurality of ports adapted to direct a current of fluid angularly into 15 said pocket, a valve for opening and closing said ports, a valve stem with a reduced portion to fit within said neck, and a connection between said valve stem and said hand grip, substantially as described.

20 5. In a device of the class described, a
casing comprising a cylinder having a re-
duced neck adapted to be connected to a
source of compressed fluid, a hand grip
mounted for rotation upon said neck, a ro-
25 tary piston within said cylinder provided
with a circular series of pockets, a spindle
adapted to be rotated by said piston, a head
adjacent said piston and provided with an-
gularly disposed ports adapted to direct a
30 stream of fluid angularly into said pockets,
a ring mounted for rotation upon said head
and provided with openings for registration
with said ports, a valve stem connected at
one end to said ring and reduced at the op-
35 posite end to fit within the reduced neck of
said casing, and a connection between said
valve stem and said hand grip, substantially
as described.

as described.

6. In a device of the class described, a
40 casing comprising a cylinder provided at
one end with a reduced neck and at the
opposite end with a housing, a worm shaft
in said housing mounted to extend at one
end into said cylinder, a worm wheel mount-
45 ed upon a spindle in mesh with said worm,
a rotary piston mounted upon the said ends
of said worm shaft provided adjacent its
periphery with a circular series of vanes, a
head within said cylinder adjacent said pis-
50 ton provided with oppositely disposed an-
gularly inclined ports whereby air may be
directed angularly against said vanes, a
valve for controlling the flow of air to said
ports, said valve provided with a reduced

stem adapted to fit within said reduced neck, a rotatable hand grip on said reduced neck, a connection between said hand grip and said valve stem and means for admitting fluid under compression to said reduced neck, substantially as described. 60

7. A casing comprising a cylindrical housing, a tubular barrel substantially tangential thereto and in communication therewith, and an enlarged cylinder forming an extension of said barrel and co-axial therewith, said housing being open at its ends, in combination with a pair of heads detachably secured to said housing and closing the respective ends thereof, bearings in said heads, a spindle mounted in said bearings, a tool holder secured upon one end of said spindle and a worm gear secured to said spindle within said housing and communicating with said barrel, a worm in said barrel in mesh with said gear, said worm being extended at one end into said cylinder, and means operable by fluid pressure upon said end for rotating said worm, substantially as described. 75

8. A casing comprising a cylindrical housing, a tubular barrel substantially tangential thereto and communicating therewith and an enlarged cylinder forming an extension of said barrel and co-axial therewith, said housing being open at its ends, in combination with a pair of heads detachably secured to said housing and closing the respective ends thereof, removable bearings in said heads, a spindle mounted in said bearing, a tool holder secured upon one end of said spindle and a worm gear secured to said spindle within said housing and communicating with said barrel, removable bearings in said barrel, a worm mounted for rotation in said bearings in mesh with said worm gear, one end of said worm being reduced and extended into said cylinder, a rotary piston adapted to be operated by fluid pressure upon said end, and means for controlling the pressure of said fluid upon said piston, substantially as described. 100

In testimony whereof I have signed my name to this specification in the presence of two subscribing witnesses.

OSCAR W. NORBERG.
